UNITED STATES PATENT OFFICE

2,515,315

TILT LOCKING BREECHBLOCK FOR
AUTOMATIC FIREARMS

Dieudonné Joseph Saive, Wandre, Belgium

Application July 18, 1947, Serial No. 761,794
In Belgium December 13, 1943Section 1, Public Law 690, August 8, 1946
Patent expires December 13, 1963

4 Claims. (Cl. 89—184)

1

This invention relates to automatic firearms having fixed barrels and in which the breech block is opened by a slide acted upon by the explosion gases.

In firearms of this type, the extraction of the empty cartridges is sometimes rendered difficult by the too sudden recoil of the breech block.

According to the present invention, there is provided in the breech block housing a right-angled lever, the two arms of which are unequal. The long arm is positioned along the slide and has its end in the shape of a cam coming into contact with a cam of the slide. The end of the other arm bears on the front surface of the breech block.

In this way, from the beginning of the recoil, the slide acts on the breech block through the medium of the lever and the extractor exerts a strong action slowly applied to the cartridge to be extracted.

In a preferred form of the invention, a spring is positioned between the breech block and the slide and tends constantly to separate these two parts, so that the breech block is forcibly locked when it reaches its forward position. Moreover, this spring is provided with a spur which extends into a groove in the firing pin and holds it until the breech block is closed.

The rear part of the slide is, moreover, configured to prevent the striking hammer from striking the firing pin as long as the breech block is not locked. Finally, the slide is provided, adjacent its rear end, with a cam, of which the rounded surface comes successively into contact with an abutment having three surfaces, said abutment being integral with the movable breech block. By bringing this cam into contact successively with the three surfaces of the abutment, the breech block is thrust forwardly, placed in locking position and finally fixed in this position.

In order that the invention may be properly understood and be more readily carried into effect, an example of an automatic firearm embodying the invention will now be described with reference to the accompanying drawings in which:

Fig. 1 is a longitudinal vertical section through the firearm showing the breech block and the slide which unlocks and opens the breech block and causes it to recoil. The upper part of the figure is a section taken on the plane I—I in Figures 2, 3 and 5; the left hand lower part is an elevation taken in the direction F¹ in Figure 2, the breech block being omitted; the right hand

2

lower part is a section taken on the plane Ia—Ia in Figures 2, 3, 5 and 7.

Figure 2 is a plan view of the slide.

Figure 3 is an end view of the slide taken in the direction F² in Figure 2.

Figure 4 is a cross-section through the receiver taken on the line IV—IV in Figure 1.

Figure 5 is an end view of the breech block.

Figure 6 is a side elevation of the breech block.

Figure 7 is a section taken on the line VII—VII in Figure 6.

Figure 8 is a similar view as Figure 1 but in which the slide starts to move backwards.

Figure 9 is a similar view as Figure 1 in which the breech block is unlocked.

Figure 10 is a similar view as Figure 1 in which the breech block is opened.

Figure 11 is a partial sectional view showing the cooperating rear parts of the slide and the 20 breech block respectively in the positions they assume during the return movement of the breech block, when the return movement starts.

Figure 12 is a similar view as Figure 11 but at the instant at which the breech block reaches the 25 locking position.

Figure 13 is a similar view as Figure 12 but when the breech block is locked.

Figure 14 is a longitudinal central sectional view showing the parts and particularly the slide and the breech block in the positions they assume 30 at the end of recoil.

When the explosion occurs, the gases act on a piston 1 which urges the slide 2 backwards against the resistance of a spring 7, the end of 35 which lies within the hollow part of the slide.

The first function of the slide is to unlock the breech block 3. This it does through the ramp 2a which presses against a lug 3a on the breech block and lifts the rear end of the breech block as shown in Figures 8 and 9 so that the locking member 3b rises clear of the locking member 4a of the receiver and so that the lower face 3c of the face 4d of the breech block locking member 4a (Figure 10).

As shown in Figure 8, the lug 3a on the breech block is in contact with the ramp 2a of the slide. At that instant, that inner rear part of the slide which maintained the breech block locked is withdrawn.

The second function of the slide is to cause the breech block to be opened and the empty cartridge case to be extracted. These operations are initiated by a lever 5 pivotally mounted on the receiver at 5a. The longer arm of this lever 55 is provided with a cam surface 5b which is acted

upon by a cam **2b** on the slide when the latter has unlocked the breech block (Figures 9 and 10). The lever is consequently swung in the sense of the arrow **Y** (Fig. 10) so that the end **5c** of its shorter arm presses against a projection **3d** on the front end of the breech block.

According to Figure 9 the breech block has reached its uppermost position and the unlocking of the latter is achieved. Thereafter the lever **5** operates and comes in contact with ramp **2b** of the slide. That way, the lever **5** causes backwards effort of the slide to be transmitted to breech block **3d** by means of the shorter arm **5c** of said lever.

The lever **5** increases the mechanical advantage of the mechanism, ensuring that the breech block is first of all moved back slowly so that it exerts a strong and slowly applied force for the extraction of the empty cartridge case. When the extraction has been thus initiated, the projection **2c** on the slide abuts against a projection **2e** on the breech block (Figure 10) so that the breech block is then moved back rapidly into the fully open position with and by the slide.

In Figure 10, the extraction of the breech block and of the empty cartridge case are completed and projection **2c** on the slide moves the breech block **3** backwardly.

The slide acts in the same way, of course, when the breech block is opened by hand by means of the lever **2e** (Figure 3).

It will be seen from Figure 4 that the lever **5** is mounted obliquely relatively to the receiver **4**.

The recoil of the breech block **3** causes the striker **33** pivotally mounted at **33a** (Figure 1) to swing back through a groove **4c** in the receiver, so that said striker can resume its backwards position ready for striking the firing pin.

The slide returns to the closed position under the action of its return spring **7** moving the breech block with it. During the return movement (Figures 11-13), the curved face **2d** (Figs. 11, 12, 13) of a part of the slide bears against the steeply sloping surface **3f** on the lug **3a** of the breech block (Figure 11) until the breech block reaches the locking position (Figure 13).

When the locking position is reached, the forward movement of the breech block is arrested abruptly by the abutment of the part **3i** against a part fixed to the barrel, the rear portion of the breech block is pushed down namely by a spring **32** arranged between the breech block and the slide and is locked by the locking member **4a**. The slide continuing to move forward and its part **2d** riding up the more gently sloping face **3g** (Figure 12) on the lug **3a** of the breech block helps to force the breech block down. Finally, the part **2d** on the slide comes on to the horizontal face **3h** (Figure 13) on the lug **3a** so that the slide holds the breech block against being unlocked.

In Figure 13 is shown the locking reliability area; the part **2d** of slide, covering surface **3h** of the breech block according to the backwards movement of slide appears in relation with the slide positions shown in Figures 1 and 8.

The spring **32** also forms a safety device (Figure 14) for preventing firing when the breech block is unlocked. As shown in Figure 14, the firing pin **31** has a groove **31a** in it and the spring **32** has a lug **32a** on it which acts as a safety and, by engaging in the groove **31a**, holds the firing pin against forward movement when the breech block is unlocked.

When the breech block is not locked (Figure 8), the rear end of the slide projects beyond the rear end of the firing pin thus preventing the striker from striking said firing pin.

5 What I claim is:

1. An automatic firearm comprising a fixed barrel, a receiver fixed to said barrel, a slide and a breech block reciprocating in said receiver, a striker, a firing pin, a safety spring located between and tending to separate said breech block and said slide, a lug on said breech block, a curved face on said slide coacting with said lug on said breech block to move said breech block forwardly and to hold it in locked position, a lever pivotally mounted in said receiver so that one of its extremities comes in contact with said slide while the other extremity rests upon the fore face of said breech block, said slide having its back part in the path of said striker as long as said slide has not reached its forward position.

2. An automatic firearm comprising a fixed barrel, a receiver fixed to said barrel, a slide and a breech block reciprocating in said receiver, a striker, a firing pin, a safety spring located between and tending to separate said breech block and said slide, a lug on said breech block, a curved face on said slide coacting with said lug on said breech block to move said breech block forwardly and to hold it in locked position, a cam on said slide, a lever pivotally mounted in said receiver and having two unequal arms perpendicular to one another, the extremity of the longer arm located along a side wall of said receiver being in contact with said cam on said slide while the extremity of the other arm rests upon the fore face of said breech block, said slide having its back part in the path of said striker as long as said slide has not reached its forward position.

3. An automatic firearm comprising a fixed barrel, a receiver fixed to said barrel, a slide and a breech block reciprocating in said receiver, a striker, a firing pin, a safety spring located between and tending to separate said breech block and said slide, a lug on said breech block, a curved face on said slide coacting with said lug on said breech block to move said breech block forwardly and to hold it in locked position, a cam on said slide, a lever pivotally mounted in said receiver, said lever being inclined with respect to said side wall of said receiver and having two unequal arms perpendicular to one another, the extremity of the longer arm located along a side wall of said receiver being in contact with said cam on said slide while the extremity of the other arm rests upon the fore face of said breech block, said slide having its back part in the path of said striker as long as said slide has not reached its forward position.

4. An automatic firearm comprising a fixed barrel, a receiver fixed to said barrel, a slide and a breech block reciprocating in said receiver, a striker, a firing pin, said firing pin having a groove therein, a safety spring located between and tending to separate said breech block and said slide, a hook on said spring engaging with said groove in said firing pin as long as said breech block is not locked, a lug on said breech block, a curved face on said slide coacting with said lug on said breech block to move said breech block forwardly and to hold it in locked position, a cam on said slide, a lever pivotally mounted in said receiver, said lever being inclined with respect to said side wall of said receiver and having two unequal arms perpendicular to one another,

the extremity of the longer arm located along a side wall of said receiver being in contact with said cam on said slide while the extremity of the other arm rests upon the fore face of said breech block, said slide having its back part in the path of said striker as long as said slide has not reached its forward position.
